[57]**CLAIM**

The ornamental design for an electrical terminal, as shown and described.

DESCRIPTION

FIG. 1 is a perspective view of an electrical terminal showing my new design;

FIG. 2 is a front elevation view thereof;

FIG. 3 is a top plan view thereof;

FIG. 4 is a side elevation view thereof, the side opposite being a mirror image to the side shown;

FIG. 5 is a bottom plan view thereof; and,

FIG. 6 is a rear elevation view thereof.

The broken line showing throughout the drawing disclosure is included for the purpose of illustrating environmental structure only and forms no part of the claimed design.
